(57) **CLAIM**

The ornamental design for a skin care device, as shown and described.

DESCRIPTION

FIG. 1 is a perspective view of the skin care device showing my new design;

FIG. 2 is a front elevation view thereof;

FIG. 3 is a rear elevation view thereof;

FIG. 4 is a left side elevation view thereof;

FIG. 5 is a top plan view thereof; and,

FIG. 6 is a bottom plan view thereof.

The broken lines shown in the figures are included for the purpose of illustrating portions of the skin care device and form no part of the claimed design.
